UNITED STATES PATENT OFFICE.

EDMUND McDONALD, OF BALTIMORE, MARYLAND.

WRENCH.

Application filed April 12, 1922. Serial No. 552,194.

To all whom it may concern:

Be it known that I, EDMUND McDONALD, a citizen of Canada, residing at Baltimore, in the county of Baltimore and State of Maryland, have invented certain new and useful Improvements in Wrenches, of which the following is a specification.

This invention relates to wrenches especially adapted for use on pipes.

10 Briefly stated, an important object of this invention is to provide a pipe wrench capable of being used in close places and having simple means whereby a positive grip may be obtained on the pipe to be turned.

15 Also, the invention aims to provide simple means whereby the jaw of the wrench may be conveniently released from positive engagement with the pipe.

20 A further object is to provide a pipe wrench which is of highly simplified construction, durable in use and cheap to manufacture.

25 Other objects and advantages of the invention will be apparent during the course of the following description.

In the accompanying drawing forming a part of this application and in which like numerals are employed to designate like parts throughout the same,

30 Figure 1 is a perspective of the improved wrench in use.

Figure 2 is an enlarged detail sectional view through the same.

Figure 3 is an end elevation of the wrench.

35 In the drawing, wherein for the purpose of illustration is shown a preferred embodiment of the invention, the numeral 5 designates a tubular handle of any desired size and material and which is provided at its

40 forward end with a socket member 6 having an attaching stem 7 secured in the forward portion of the handle by means of a rivet 9 or other suitable fastening device. The rear portion of the socket member 6 is formed 45 with an annular shoulder 10 which flatly abuts the forward end of a collar 11 threaded on the handle so that the socket member is securely braced and held against movement with relation to the handle.

50 In carrying out the invention, the socket member 6 is interiorly screw threaded for the reception of an exteriorly threaded tubular member 14. As illustrated in Figure 2, the forward end of the tubular member 14 55 is provided with a head 16 having a pair of ears 17 at one end and a pair of hooks

18 at the other end. The ears 17 are permanently connected to a chain or other flexible element 20 by means of a pin 22. The intermediate portion of the chain may be 60 adjustably connected to the hooks 18 by means of the pins 24 of the several links for accommodating pipes of different diameters.

As illustrated in Figure 2, a jaw 30 is slidably arranged in an opening 31 in the head 16 and is provided with a rearwardly directed shank 34 slideable through the tubular member 14. The shank 34 is extended beyond the rear end of the tubular member 14 and is provided with a coil spring 36 70 which is confined between the rear end of the tubular member and a stop pin 38 carried by the rear end of the shank. In operation, when it is desired to engage the jaw 30 with the pipe, the handle 5 is turned 75 counter-clockwise as viewed in Figure 1 so as to engage the rear end of the socket 40 with the rear end of the shank 34 and thereby advance the same. The movement of the shank of course engages the jaw 30 with the 80 pipe so that a positive driving connection is provided.

On the other hand, when it is desired to release the jaw 30 the handle 5 and the socket member 6 are turned clockwise as 85 viewed in Figure 1 so as to permit the coil spring 36 to retract the jaw 30.

With reference to the foregoing description taken in connection with the accompanying drawing, it will be seen that a 90 wrench constructed in accordance with this invention may be conveniently connected to a pipe and operated in extremely close quarters.

I claim:—

1. A wrench comprising a handle, a socket member secured on the forward end thereof and having a longitudinally extending socket, a tubular member threaded into said socket and having a head formed with pairs 100 of hooks and ears, a chain permanently connected to said ears and adjustably connected to said hooks, a jaw slideable through said head and having a shank slideable through the tubular member, the rear end of said 105 socket being adapted to engage the rear end of the shank, whereby the advancement of the socket member on said tubular member will advance the shank and jaw.

2. The construction set forth in claim 1, 110 and a coil spring confined between the rear end of the tubular member and the rear end

of the shank for urging the jaw to its retracted position.

3. The construction set forth in claim 2, an attaching stem carried by the rear end 5 of said socket member and secured within said handle, and a collar arranged on the forward end of said handle and flatly engaged by the rear portion of said socket member.

10 4. A pipe wrench comprising a handle, a socket member secured on the forward end thereof and having a longitudinally extending socket, a tubular member threaded into

said socket and having a head, a jaw freely slidable through said head and having a 15 shank slidable through said tubular member, pipe engaging means carried by said head, and a coil spring associated with said shank and urging the same to retracted position.

In testimony whereof, I have affixed my 20 signature in the presence of two witnesses.

EDMUND McDONALD.

Witnesses:

FRANK MYERS,
DAVID L. LEONARD.
